COMBINED CHEESE SLICER AND BOARD

Michael Lax, 68 E. 91st St., New York, N.Y. 10028

Filed June 23, 1972, Ser. No. 265,471

Term of patent 14 years

Int. Cl. D7—01, 04

U.S. Cl. D7—43

FIG. 1 is a top plan view of a combined cheese slicer and board showing my new design, the slicer being shown in its retracted position;

FIG. 2 is an elevational view thereof as seen from one side thereof;

FIG. 3 is an elevational view thereof, as seen from one end thereof;

FIG. 4 is an elevational view thereof, as seen from the other side thereof;

FIG. 5 is an elevational view thereof, as seen from the other end thereof; and

FIG. 6 is a perspective view thereof, the slicer being shown in its raised position.

I claim:

The ornamental design for a combined cheese slicer and board, substantially as shown and described.
